UNITED STATES PATENT OFFICE.

FRANK W. COLLINS, OF MORAVIA, NEW YORK.

IMPROVEMENT IN RAILWAY-SWITCHES.

Specification forming part of Letters Patent No. 155,791, dated October 13, 1874; application filed July 21, 1874.

To all whom it may concern:

Be it known that I, FRANK W. COLLINS, of Moravia, in the county of Cayuga, State of New York, have invented certain new and useful Improvements in Automatic Railway-Switches; and do hereby declare that the following is a full, clear, and exact description thereof, reference being had to the accompanying drawings making a part of this specification, in which—

Figure 1 is a perspective view of a switch operated by my improved mechanism. Fig. 2 is a like view of said mechanism detached from the rails. Fig. 3 is a front elevation of the operative parts and of the front end of a locomotive provided with mechanism for shifting the switch-rails. Figs. 4 and 5 are plan views of shaft and cams employed for moving the switch-rails, said parts being shown in different positions. Fig. 6 is a plan view of the lower side of the truck, showing the means employed for operating the roller-bar; and Fig. 7 is a side elevation of the same.

Letters of like name and kind refer to like parts in each of the figures.

The design of my invention is to enable a railroad-switch to be changed, as desired, by the passage of a locomotive or car over the track leading to the same; and it consists, principally, in the means employed for communicating motion from the engine or car to the cam-shaft which moves the switch-rails, substantially as and for the purpose herein-after shown.

It consists, further, in the means employed for moving to and securing in position the adjustable roller-bar, substantially as is hereinafter shown and described.

It consists, finally, in the means employed for operating the switch by hand, substantially as is hereinafter specified.

In the annexed drawings, A and A represent the rails of a main track; B and B, the end rails of a side track; and A' and A', switch-rails, which are pivoted in place at one end, and at their opposite ends are capable of being moved laterally until they coincide with the contiguous ends of the rails of either said main or side tracks, all in the usual manner.

Journalized within suitable bearings, C and

C, beneath the forward ends of the switch-rails A' and A', is a shaft, D, which at each end is provided with a crank-arm, d, while immediately inside of each of said bearings C is provided a cylindrical enlargement, D', that upon its inner end is cut away upon the lines shown in Figs. 4 and 5, so as to form at such point a curved cam-face, d'. From the lower side of the tie-bar E, which connects the forward ends of the switch-rails A' and A', two studs, e and e, project downward and serve as pivotal bearings for two rollers, e' and e', the latter of which parts are relatively arranged so as to bear upon the faces d' and d' of the cams D' and D'.

The faces d' and d' of the cams D' and D' are reversed, so that when the shaft D is partially rotated in either direction one of said cams will bear against and force the contiguous roller e', and with it the switch-rails, toward the opposite side of the track, while the opposite cam will permit its roller to move freely in the direction named.

Upon reversing the motion of the shaft the cam-face, which before receded, will be moved forward and press its roller in a lateral direction, while the opposite cam-face will recede and permit its roller to move toward its side of the track, such arrangement of parts enabling said switch-rails to be moved in either direction.

In order that the switch-rails may be locked in place at the limit of their motion in either direction, at each end of each cam-face d' the end of the cam D' is concentric with the shaft D, so that when the roller e' impinges upon said portion d'' no lateral pressure which may be applied to said roller will cause said cam to rotate. The opposite roller d', being at the same instant in contact with the locking-face d'' of its cam, prevents movement of the switch in such direction.

The operating-shaft D is moved by the following-described mechanism: A bar, F, is pivoted near its center to or upon each crank d, and at each end is in like manner connected to or with one corner of a quadrant or bell crank, G, that is pivoted upon a suitable support in a line with said crank.

To the opposite corner of each bell-crank G is pivoted one end of a rod, H, which from thence extends upward and has its opposite

end in a like manner pivoted upon the free end of a lever, I, which is placed parallel to and upon a line horizontally with the track, and has its opposite end pivoted upon a suitable support.

The levers I and I upon each side of the track are so arranged as that when pressed down to a horizontal position they shall, through the intermediate mechanism, move the switch-rails toward their side of the track, and at the same time shall raise the levers upon the opposite side of said track, one pair of levers being raised as the opposite pair are depressed.

In order that the switch may be operated from or by the engine, a bar, K, is placed transversely within suitable bearings beneath the front end of the forward truck L, and is arranged to move longitudinally within the same.

The length of the bar K is such that when caused to project to equal distances from the opposite sides of the engine it will pass between the levers I and I, but when moved longitudinally to either limit its projecting end shall come into contact with the lever upon that side and press the same downward to a horizontal position.

The ends of the bar K are provided with rollers k, in order that the friction upon the levers I and I may be lessened, while, in order that the shock caused by striking the latter when at a high rate of speed may be avoided, said levers are made concave, longitudinally, upon their upper sides.

As thus constructed the inclination of said levers is at first slight, but increases regularly, and causes the passage of an engine to move the switch with uniform speed from the instant that the roller-bar comes into contact until it leaves said levers.

Were the levers I and I straight, they would be moved their entire distance by the first contact of the roller-bar, and thereby a sudden and injurious shock would be transmitted to the connecting mechanism.

By increasing the length of the curved levers the time in which the switch will be changed for a given velocity of the engine will be correspondingly increased.

The roller K is moved longitudinally within its bearings by means of an L-shaped lever, M, which is pivoted to or upon the lower side of the truck-frame and has its forward end m engaged with a corresponding notch, k', that is formed at or near the center of said bar.

From the opposite end of the lever M a rod, N, extends rearward and connects the same to or with the lower end of a lever, O, which is suitably pivoted upon the truck and extends upward within convenient reach of the operator's hand.

The lever O is arranged to move in a line with the track, and by moving its upper end forward or back the bar K will be correspondingly moved in a lateral direction. A quadrant, P, is attached to or upon the truck,

and, extending upward beside said lever, is provided within its contiguous face with a series of notches with which said lever engages when adjusted to position.

The switch thus operated is under complete control of the engineer by means of the hand-lever O, and its connecting mechanism can cause the roller-bar K to move said switch to either side, such movement being certain, easy, and safe.

In order that the switch may be operated by hand, when necessary, without hampering it by other mechanism when it is to be operated by the engine, one end of the cam-shaft D is squared and a corresponding open end of a lever, Q, fitted upon the same.

The lever Q is pivoted, at or near its upper end, upon a bar, R, which bar at its lower end is pivoted upon a suitable support, with its bearing in a line with the axis of the shaft D, said lever being arranged to move upon said bar in a plane which corresponds to the line of said shaft.

As thus arranged, it will be seen that by moving the upper end of the lever Q outward its lower end, when brought into proper relative position with the end of the shaft D, will engage therewith, after which, by moving said lever and the bar R upon the axial bearing of the latter, said shaft will be rotated and the switch changed.

A spring, S, placed between the upper ends of the lever Q and bar R, throws the lower end of the former out of engagement with the shaft D as soon as released, by which means the latter and the mechanism of the switch are left free to be moved by the engine.

The invention described possesses all the advantages of the usual hand-switch, and at the same time is capable of easy and safe operation by the engineer, without arresting the speed of the engine.

Having thus fully set forth the nature and merits of my invention, what I claim as new is—

1. In combination with the cam-shaft D, provided with the cranks d and d, the bars F and F, the bell-cranks G and G, the rods H and H, and the levers I and I, said parts being constructed to operate in the manner and for the purpose substantially as shown.

2. In combination with the longitudinally-adjustable roller-bar K, provided with the notch k', the lever M m, the rod N, the lever O, and the quadrant P p p, substantially as and for the purpose specified.

3. In combination with the cam-shaft D, the lever Q, pivoted to or upon the pivoted bar R and capable of engaging with the end of said shaft, substantially as and for the purpose shown.

In testimony whereof I hereunto set my hand this 18th day of July, 1874.

FRANK W. COLLINS.
